CLOCK OR SIMILAR ARTICLE

William V. Judson, Dover, Mass., assignor to General Electric Company, a corporation of New York

Application May 2, 1957, Serial No. 45,978

Term of patent 14 years

(Cl. D42—7)

Fig. 1 is a front elevational view of a clock embodying my new design;

Fig. 2 is a side elevational view of the clock shown in Fig. 1;

Fig. 3 is a fragmentary cross-sectional view of a portion of the clock shown in Fig. 1 taken along the line 3 of Fig. 1; and

Fig. 4 is a fragmentary cross-sectional view of a portion of the clock shown in Fig. 1 taken along the line 4—4 of Fig. 2.

The opposite side of the clock is the same in appearance as the side shown. The back of the clock is substantially plain.

I claim:

The ornamental design for a clock or similar article, substantially as shown and described.
